[57] CLAIM

The ornamental design for a stroller for an infant, as shown and described.

DESCRIPTION

FIG. 1 is a front, top and side perspective view of the stroller for an infant with the flap partially open; FIG. 2 is a front elevational view thereof with the flap closed;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.

FIG. 1.

FIG. 2.

FIG. 6.

FIG. 3.

FIG. 4.

FIG. 5
